MACHINE FOR MOLDING RODS

Nicholas Corsi, Brooklyn, N. Y.

Application July 8, 1936, Serial No. 89,567

3 Claims. (Cl. 18—5)

The invention relates to machines for making rods of plastic material particularly cork rods. It has for its main object to provide a machine which will greatly increase the production of such rods, which will produce a rod of a much more even texture throughout its whole length, and which will occupy considerably less space, considering its capacity, than other machines performing work of this type.

Another object is to provide a machine which requires no skilled operator, which is practically automatic in its operation, which will thoroughly agitate and properly feed the material used for making the rods, which has no parts easily broken or apt to get out of order, and which can be manufactured and operated at a comparatively low cost.

These and various other objects and advantages will be readily understood from the following description and from the accompanying drawings of a preferred embodiment of the invention, in which, however, modifications may be made without departing from the scope of the appended claims. In the drawings

Fig. 1 is a front elevation of the machine,

Fig. 2 is a side elevation,

Fig. 3 is a cross-sectional plan view shown approximately on lines 3—3 in Fig. 1.

Fig. 4 is a front elevation of the chain feeding mechanism,

Fig. 5 is a fragmental view showing the chain construction and the tube release mechanism,

Fig. 6 is a bottom view of a link of the upper chain,

Fig. 7 is a side view of the hopper with the side wall removed,

Fig. 8 is a fragmental top view of Fig. 7, and

Fig. 9 is a slight modification of the operating lever for the chain operating mechanism.

Referring now to all the views, simultaneously, the machine consists of a stand or table 10 having legs 11. On the top of this stand two posts 12 and 13 are mounted and these posts support a cross beam 14 which extends transversely over the stand at a considerable height above it. Forwardly-extending brackets 15 and 16 and rearwardly-extending brackets 17 and 18 are formed on the stand and from these brackets, tie rods 19 are connected to the cross beam 14 to steady it. The tie rods are provided with turn buckles 20 to tighten them. A main shaft 21 is mounted in the stand and this shaft is preferably driven from a motor 22 through a speed reducing device 23. Pinions 24 are secured to the outer end 55 of the main shaft and these pinions drive a pair

of large gears 25, mounted on the ends of a shaft 26, likewise mounted in bearings on the stand.

Crank pins 27 are provided on the outer sides of the gears 25 and on these crank pins connecting rods 28 are mounted. The other end of the connecting rods are connected to studs 29 secured on the ends of a cross head 30. This cross head is provided with sleeves 31 which engage slidably on the posts 12 and 13 so that when the gears 25 are turned, the cross head will slide up and down on these posts.

A pair of vertical supports 32 and 33 are mounted on top of the table and on these posts sleeves 34 and 35 are free to turn. Each of these sleeves, one of which is shown in detail in Fig. 4, is provided with a sprocket wheel 36 near its upper end and another sprocket wheel 37 near its lower end. A chain 38 is mounted on the lower sprocket wheel and another chain 39 on the upper sprocket wheel. These chains will be described in detail later.

Referring now particularly to Figs. 1, 3 and 4, the chains are operated by the following mechanism. A pair of outer guides 40 and 41 are mounted on the table as plainly shown in Fig. 3, as is also an inner guide 42. A bar 43 is slidably moved between the guides 41 and 42. This bar is provided with a pawl 44 at its outer end and this pawl is held in engagement with the teeth of a ratchet wheel 45 by means of a spring 46. The ratchet wheel is made integrally with the sleeve 34 and consequently with the sprocket wheels 36 and 37 of that sleeve.

An operating bar 47 is slidably mounted in a bracket 48 secured to the cross head 30. This operating bar is provided with a pin 49 at its upper end which engages on top of the bracket 48 so that the operating bar will be lifted with the cross head. The lower end of the operating bar is provided with sidewardly extending angular faces 50 and 51 and the lower end of the bar is free to move in an opening 52 formed in the inner guide 42. A roller 53 is secured to the bar 43.

It will be evident that, when the operating bar 47 is lifted by the cross head 30, the face 50 will engage with the roller 53 and thus cause the bar 43 to be moved sidewardly so that the pawl 44 engaged on the end of this bar will cause the sprocket wheel 45 to rotate one tooth. As the operating bar 47 is again lowered the bar 43 is returned to its normal position by a flat spring 54.

Another bar 55 is slidably mounted between the guides 40 and 42. This is likewise provided with a roller 56 which engages on the angular face 51. When the operating bar 47 is lifted the

roller is pushed sideward and so, consequently, is the bar 55. The outer end 57 of this bar engages in one of the ratchet teeth, as plainly shown in Fig. 3, during the main part of the 5 reciprocating movement of the cross head 30, so as to prevent rotation of the chains during this operation. It is pulled out of engagement while the pawl 44 moves the ratchet wheel 45 one tooth. The bar 55 is held in its normal position by a 10 spring 58. In other words, when the operating bar 47 is lifted the end 57 is pulled out of engagement with the ratchet wheel while the pawl 44 turns the ratchet wheel.

Fig. 9 shows a slight modification of the operating bar. In this case the operating bar 47A, instead of being provided with angular faces, have been provided with angular slots 50A and 51A in which the rollers 53 and 56 engage. This construction makes the operation of the bars 43 20 and 55 possible so that the springs 54 and 58 may be dispensed with.

Reference is now made particularly to Figs. 5 and 6, and the chains 38 and 39 will now be described in detail. A carrier member 59 is secured to the lower side of the chain 38 and is provided with a small rounded button 60 of sufficient size to fit within one of the tubes 61, in which the rods are molded. The upper chain 39 has a carrier 62 secured to its upper side and 30 this carrier member has a downwardly-extending portion 63 in which a semi-circular opening 64 is formed, as plainly shown in Fig. 6. A hole 65 is drilled in the member 62 to align with the opening in the tube 61. A spring 66 is secured 35 in the member 63 in such a manner that its ends 67 will hold the upper end of the tube in the semi-circular opening 64. The carrier members 59 slide on rails 68 and 69 mounted on the stand, as plainly shown in Figs. 2 and 3.

40 A hopper 70 is mounted on the table by means of two columns 71 and 72. The lower and forward end 73 of this hopper extends in over the rear part of the upper chain, as plainly shown in Fig. 2. Reference is now also made to Figs. 45 7 and 8. A plurality of circular openings 74 are provided in the lower side of the forward end 73 of the hopper and these holes align with the holes 65 in the upper chain members, so that material from the hopper may be fed into the 50 tubes held by the chains. A slide 75, provided with semi-circular notches 76, is mounted in the lower part of the hopper and employed to alternately open and close the holes 74.

55 This slide is operated in the following manner. A lever 77 is mounted on the side of the table 10 on a screw 78 and is provided with a roller 79 which is adapted to engage on a cam part 80 mounted on the inner side of the rim of one of the gears 25. The free end of the lever 77 60 is connected, by means of a connecting rod 81, to a lever 82 and this lever is secured to a shaft 83 on which a plurality of levers 84, located inside of the hopper, are rigidly connected. These levers 84 are connected to the slide. The lever 82 is preferably lengthened and a weight 85 suspended from its free end, so as to aid in the 65 operation of the mechanism and also to impart a certain jar when the slide is closed. It is evident that as the gear 25 rotates the roller 79 70 will be lifted by the cam member 80 and thus the slide will open. When the cam member reaches the point shown in Fig. 2, it is also evident that the lever 77 will be caused to drop, the weight 85 aiding in this, and thus the slide 75 will 75 be closed.

An agitator 86, provided with a plurality of arms 87, is mounted crosswise in the hopper to stir up its contents. This agitator is mounted on a shaft 88. A pusher 89 is likewise mounted inside of the hopper and employed to crowd its 15 contents towards the front of the hopper. This pusher is operated by a link 90 actuated by a crank shaft 91. A sprocket gear 92, shown only in Fig. 1, drives another sprocket gear 93, shown only in Fig. 3, by means of a chain 94. The 10 sprocket gear 93 is rigidly connected to another sprocket gear 95. The shaft 88 carries a sprocket gear 96 on its outer end and the crank shaft 91 carries a sprocket gear 97. These two sprocket gears are driven by a chain 98 which receives its 15 power from the sprocket gear 95. Another slide 99 is adjustably secured in the hopper, as shown in Figs. 7 and 8, and provided with fingers 100 at its lower edge. As the material from the hopper is crowded into the forward end of the hopper 20 by the pusher 89, it is broken up by being passed between these fingers.

A plurality of plungers 101 are slidably mounted in the cross head 30 and suspended from the cross head by means of collars 102. These plungers are so arranged in the cross head that they are aligned with the openings 65 in the upper chain and consequently with the tubes 61 held in the chain. While, as said, the upper end of the plungers are supported in the cross head 30, the 30 lower ends are supported in a cross bar 103 contained under the upper side of the forward end of the hopper 70. Each of the plungers is provided with a collar 104 which is rigidly secured to the plunger and on top of which a compression spring 105 is placed. These collars are placed at gradually increasing distances below the cross head, as plainly shown in Fig. 1. The reason for this will be explained when the complete operation of the machine is described. 40

To counterbalance the weight of the cross head 30, sheaves 106 are mounted on top of the machine. Cables 107 pass over these sheaves, each having one end secured to the cross head and the other end passes over another sheave 108. 45 These last-mentioned sheaves are mounted on the outer ends of the arms 17 and 18. Counterweights 109 are suspended from the free ends of the cables.

A pulley 110 is mounted on the shaft 26, as 50 shown in Fig. 1. This pulley, as shown in Figs. 2 and 3, drives a belt 111 mounted on a second pulley 112, secured on the shaft 113 on which a wider pulley 114 is also mounted. The shaft is supported in bearings 115 mounted on a stand 55 116 and a conveyor belt 117 is driven by the pulley 114 and another pulley contained underneath the table 10.

A collar 118, having a forwardly-extending bearing 119, is rigidly secured on the post 13. 60 A short shaft 120 is mounted in the bearing 119 and on one end of this shaft an arm 121 is secured, while on the other end a "knock-out" lever 122 is mounted. This is best illustrated in Fig. 5. The "knock-out" lever 122 is so located 65 that normally it rests against one of the tubes 61. A bar 123 has its upper end secured to the cross head 30 and its lower end adapted to engage with the arm 121 when the cross head descends, so that the "knock-out" lever 122 will force the 70 upper end of the tube out through the opening 64 in the upper carrier member 62 and cause it to fall on the conveyor belt 117, as illustrated in Fig. 3. A tension spring 124 restores the parts 75

to their normal position after the tube has been knocked out.

A container 125, for holding a quantity of suitable lubricant, is secured to the cross head 5 30. A tubular member 126 is secured to an opening in the container and this member terminates, at its lower end, in a swab or brush 127 which is aligned with one of the tubes 61 held between the chains previously described. The tubular member has a plurality of small holes in the 10 part on which the swab is secured so that lubricant from the container 125 may seep into the swab and thus lubricate the tube with which it is aligned when the cross head descends.

15 The machine operates in the following manner. A quantity of the material from which the rods are to be molded, as for example comminuted cork mixed with a suitable binder, is placed in the hopper 10 and after being agitated by the agitator 86, a quantity of the material is forced 20 between the fingers 100 by the pusher 89. In being forced between these fingers any lumps 1 which might have formed in the material are effectively broken up and the material is now 25 forced into the forward end 73 of the hopper, the slide 75 being closed.

The machine runs continuously and the operator places empty tubes in the chains by placing the lower end of a tube over the button 60 (see 30 Fig. 5) and snapping the upper end into the opening 64 between the ends 67 of the spring. A number of empty tubes are shown inserted on the left hand side of the front of the machine. Each time the cross head 30 reaches the 35 upper end of the stroke the pawl 44 turns the ratchet wheel 45 and moves all the tubes one step around.

The tubes contained in the rear part of the 40 chain, or over the rail 68, are aligned with the plungers 101. Just prior to the descent of the cross head the cam member 80 has lifted the lever 77 so that the slide 75 has uncovered the 45 openings 74 through which the plungers 101 project through the hopper. At the same time a quantity of the material from the hopper has 50 been emptied into each one of the tubes underneath the plungers. As the cross head descends the plungers descend with it. However, inasmuch as the collars 104 are not all placed the same 55 distance below the cross head, as plainly shown in Fig. 1, the descent of the plungers will arrested just as soon as the plunger rests on the top of the material in its particular tube and, only when the cross head reaches the compression springs placed on top of the collars will pressure be exerted against the quantity of material which has just entered each tube.

It will thus be seen that in the first tube to the left in the rear of the chain, only one charge 60 of material will have entered and that this charge will be compressed down in the lower end of the tube. In the second tube from the left in the rear, two charges have entered the tube, one having been compressed by the first left hand 65 plunger and the second now being ready to be compressed by the second left hand plunger. Thus as the tubes gradually progress from left to right in the rear each plunger compresses the new charge just entered, until the last right hand 70 plunger compresses the final charge and the rod is finished. Thus for each reciprocation of the cross head, a complete tube is finished at the right hand side of the rear of the chain.

The tube after being finished progresses one 75 step farther to the right when it encounters the

"knock-out" mechanism shown in Fig. 5 and is knocked from the chain in the manner previously described. The tube falls on the conveyor belt 117 from which it may be manually removed or conveyed to some other place for the next operation of extracting the molded rod after it has been baked or otherwise treated. 5

In the same manner each time the cross head descends, the swab 127 enters one of the empty tubes on the left hand side of the machine and 10 lubricates it. This lubrication serves several purposes; it reduces friction between the plungers and the tubes and it makes it easier to afterwards extract the moulded rods. 15

From the foregoing it will be seen that the only manual labor necessary is the filling of the hopper and the insertion of empty tubes in the front of the machine, otherwise the machine is completely automatic. It will also be noted that by charging the material into the tubes in small 20 quantities and compressing each of these quantities separately, the density of the finished rods will be much more uniform than if the compression was done in one operation. In fact, the more plungers employed the more uniform will 25 be the texture of the rods when finished.

While I have described and illustrated the invention as used for making round cork rods, it is evident that rods of other shapes and other materials might as readily be made on a machine 30 of this kind.

Having described the invention and its objects, what I claim as new and wish to protect by Letters Patent is:

35 1. A machine of the class described comprising a stand, a pair of vertical sleeves mounted on said stand and having sprocket wheels adjacent to their upper and lower ends, a pair of chains mounted on said sprocket wheels, said chains having means for supporting a plurality of tubes, a cross head mounted on top of the stand at a considerable distance above the upper chain, a plurality of plungers slidably mounted in said cross head, said plungers aligned with the openings in several of the tubes contained in the said chains and having operating collars secured at different distances below the cross head so that the plungers will enter their co-acting tubes to different depths, a hopper mounted above the upper chain and through one part of which hopper all of said plungers pass, means for raising and lowering said cross head while the chains are standing still and for moving said chains after the plungers are out of engagement with the tubes, and means actuated by the cross head 45 for releasing one of said tubes from the chains at each complete cycle of the cross head. 50

60 2. A machine of the class described comprising a stand, a pair of vertical sleeves mounted on said stand and having sprocket wheels adjacent to their upper and lower ends, a pair of chains mounted on said sprocket wheels, said chains having means for supporting a plurality of tubes, a cross head mounted on top of the stand at a considerable distance above the upper chain, a plurality of plungers slidably mounted in said cross head, said plungers aligned with the openings in several of the tubes contained in the said chains and having operating collars secured 65 at different distances below the cross head so that the plungers will enter their co-acting tubes to different depths, a hopper mounted above the upper chain and through one part of which hopper all of said plungers pass, means for raising 70 and lowering said cross head while the chains are standing still and for moving said chains after the plungers are out of engagement with the tubes, and means actuated by the cross head 75 for releasing one of said tubes from the chains.

are standing still and for moving said chains after the plungers are out of engagement with the tubes, means actuated by the cross head for releasing one of said tubes from the chains at 5 each complete cycle of the cross head, and a conveyor belt associated with the machine for conveying the released tubes from the machine.

3. A machine of the class described comprising a stand, a pair of vertical sleeves mounted on 10 said stand and having sprocket wheels adjacent to their upper and lower ends, a pair of chains mounted on said sprocket wheels, said chains having means for supporting a plurality of tubes, a cross head mounted on top of the stand 15 at a considerable distance above the upper chain,

a plurality of plungers slidably mounted in said cross head, said plungers aligned with the openings in several of the tubes contained in the said chains and having operating collars secured at different distances below the cross head 5 so that the plungers will enter their co-acting tubes to different depths, a hopper mounted above the upper chain and through one part of which hopper all of said plungers pass, means for raising and lowering said cross head while 10 the chains are standing still, means for moving said chains after the plungers are out of engagement with the tubes, and means actuated by said cross head for lubricating the tubes.

NICHOLAS CORSI. 15
